UNITED STATES PATENT OFFICE.

PAUL L. GEER, OF SAN JOSE, CALIFORNIA.

OIL-VAPOR-HEATING TORCH.

1,233,217.

Specification of Letters Patent. Patented July 10, 1917.

Application filed November 14, 1916. Serial No. 131,244.

To all whom it may concern:

Be it known that I, PAUL L. GEER, a citizen of the United States, and a resident of San Jose, in the county of Santa Clara and 5 State of California, have invented a certain new and useful Improvement in Oil-Vapor-Heating Torches, of which the following is a specification.

My invention relates to an improvement 10 in oil vapor heating torches, and the objects of my invention are:

First, to produce an oil vapor heating torch that can be attached to any fuel oil atomizer.

Second, to so construct an oil vapor heating torch that will produce by adjustment any degree of heat required of the same.

Third, to so construct an oil vapor heating torch that will produce the required heat 20 for bending steel plates, or expanding collars, or couplings on large shafts where an expansion is required to remove said collars or couplings from said shafts.

Fourth, to provide an oil vapor heating 25 torch that will generate the required amount of heat for shrinking large or small collars, couplings, or propeller wheels upon their respective shafts, or for any other purpose where an intense heat may be required.

I accomplish these objects by means of the 30 oil vapor heating torch illustrated in the accompanying drawings, in which:

Figure 1 is a longitudinal view of my oil vapor heating torch assembled.

Fig. 2 is a sectional view on line A—A of 35 Fig. 1 showing nozzle and combustion chamber attached thereto, with air and gas pipes in position.

Fig. 3 is an end view of Fig. 1 showing 40 outlet of nozzle and combustion chamber.

Fig. 4 is a longitudinal section on line B—B of Fig. 1 showing pipes and connections in position.

Fig. 5 is an end view of the air and gas 45 vapor distributor.

Fig. 6 is an end view of the air and gas vapor receiving connection.

Fig. 7 is a sectional view on line C—C of 50 Fig. 4 showing casing and pipes in position.

Referring now to the drawings 1 designates the main casing through which oil vapor pipe 2 and auxiliary air pipe 3 pass; said oil vapor pipe 2 and auxiliary air pipe 3 are made an integral part of casing 1, by being welded 55 to casing 1 as shown at 4, and to air and oil vapor receiver 5, as shown at 6, said air and

oil vapor receiver 5 having opening 2^c passing therethrough to opening 2^a; said air and oil vapor receiver 5 being connected to air and oil vapor distributer 7 by coupling nut 8, which in turn connects nozzle casing 9 to distributer 7, by threaded portion 10.

Connected to air and oil vapor distributer 7, by threaded portion 7^a is oil vapor pipe 11 through which oil vapor is distributed under pressure from oil vapor pipe 2 and opening 2^a in distributer 7, and through a plurality of openings 2^b in said distributer 7 to pipe opening 11^a and to combustion chamber 9^a.

Free air opening is shown at 12 in air and oil vapor receiver 5, delivering free air through said receiver 5 and through air and oil vapor distributer 7 at 12^a to pipe 13, said pipe 13 connecting with air and oil vapor distributer 7 by threaded portion 14 adapted to deliver free air to combustion chamber 9^a.

Oil vapor hose connection is shown at 15 connecting with union joint coupling 16 by threaded portion 17, said union joint coupling 16 connecting with oil vapor pipe 2 by threaded portion 18, oil vapor under pressure being controlled by valve connecting with oil vapor pressure hose which in turn connects with an oil atomizer not shown.

Auxiliary air hose connection is shown at 19 connecting with union joint coupling 20 by threaded portion 21, said union joint coupling 20 connecting with auxiliary air pipe 3 by threaded portion 22; said air being under pressure is controlled by valve connecting with air hose not shown.

Air is delivered to pipe 3 under pressure, and through opening 23 in air and oil vapor receiver 5 and to air and oil vapor distributer 7, thence through openings 24 in said oil vapor distributer 7 through a plurality of openings 24^b in distributer 7, through opening 24^a in nozzle casing 9, and from said casing 9 to combustion chamber 9^a; said combustion chamber 9^a is made of sheet steel of the required thickness and of the shape shown in the drawings, the same being hollow having an outlet 25, through which the heat is generated from the air and oil vapor mixture delivered in said combustion chamber 9^a.

A plurality of free air openings 26 are shown in combustion chamber 9^a, adapted to increase the combustion therein, said combustion chamber 9^a being connected to nozzle casing 9 by neck 9^b, is adjustable on said

nozzle casing, and held in place on nozzle casing 9 by set-screw 27.

I do not wish to confine myself as to size of my oil vapor heating torch, as the same 5 may be made of any size suitable to the work required thereof.

Having thus described my invention, what I claim as new, and desire to secure by Letters Patent, is:

- 10 1. In an oil vapor heating torch the combination of a main casing, an air pipe, an oil vapor pipe, said air pipe and said oil vapor pipe being made an integral part of said main casing, an air and oil vapor receiver, an air and oil vapor distributor, means by which said air and oil vapor receiver and said air and oil vapor distributor are connected together, a nozzle casing, means by which said nozzle casing is connected to said 15 air and oil vapor distributor, means by which said air pipe is connected to said air and oil vapor distributor, a combustion chamber, and means by which said combustion chamber is attached to said nozzle casing, said combustion chamber being adjustable on said nozzle casing, substantially as shown and described.
- 20 2. In an oil vapor heating torch the combination of a main casing, an air pipe, an oil vapor pipe, said air pipe and said oil vapor pipe being made an integral part of said main casing, an air and oil vapor receiver, an air and oil vapor distributor, a nozzle casing, a combustion chamber, a free air opening in said air and oil vapor receiver adapted to deliver free air to and through said air and oil vapor receiver and

- 35

through said air and oil vapor distributor to said combustion chamber, air pressure hose connections, means by which the same are connected with said air pipe, and means by which said air and oil vapor hose connections are connected with said oil vapor pipe, a nozzle casing, means by which said combustion chamber is attached to said nozzle casing, and a plurality of free air openings in said combustion chamber adapted to increase the combustion therein, substantially as and for the purpose described. 40

3. In an oil vapor heating torch the combination of a main casing, an air pipe, an oil vapor pipe, said air pipe and said oil vapor pipe being made an integral part of said main casing, an air and oil vapor receiver, an air and oil vapor distributor, a 45 nozzle casing, a combustion chamber, a free air opening in said air and oil vapor receiver adapted to deliver free air through said receiver and through said air and oil vapor distributor and said nozzle casing to 50 said combustion chamber, an outlet in said combustion chamber adapted to deliver the burning flame and heat therethrough, and a plurality of free air openings in said combustion chamber adapted to increase the 55 combustion therein, substantially as and for the purpose described.

In testimony whereof, I affix my signature in the presence of two subscribing witnesses, this 8th day of November, 1916.

PAUL L. GEER.
